UNITED STATES PATENT OFFICE.

ELIZABETH H. PUSEY, OF NEW YORK, N. Y.

DESIGN FOR A LUCCA SPONGE.

44,218.

Specification for Design.

Patented June 17, 1913.

Application filed February 27, 1912. Serial No. 680,328. Term of patent 3½ years.

To all whom it may concern:

Be it known that I, ELIZABETH H. PUSEY, a citizen of the United States, residing at the city of New York, in the State of New York, have invented a new, original, and ornamental Design for Luffa Sponges, of which the following is a specification, reference being had to the accompanying drawing, forming part thereof.

The figure shows a Luffa sponge in substantially the form of a doll, having a head and a hood surmounted by ears resembling those of a rabbit.

The sponge is primarily adapted for children's use.

I claim:—

The ornamental design for a sponge as shown and described.
